UNITED STATES PATENT OFFICE.

THOMAS R. PEREGOY, OF BALTIMORE, MARYLAND, ASSIGNEE TO DANIEL C. AMMIDON AND H. LYTON VARIAN, TRADING AS COPARTNERS UNDER THE FIRM-NAME OF AMMIDON AND COMPANY, OF BALTIMORE, MARYLAND.

PORTABLE SINK.

1,116,913.

Specification of Letters Patent. Patented Nov. 10, 1914.

Application filed May 23, 1914. Serial No. 840,525.

To all whom it may concern:

Be it known that I, THOMAS R. PEREGOY, a citizen of the United States, residing at Baltimore, State of Maryland, have invented new and useful Improvements in Portable Sinks, of which the following is a specification.

This invention relates to an improved auxiliary or portable sink or receptacle adapted to receive dishes, fruit, or other articles while being washed.

It is well known that porcelain lined sinks of the type usually forming part of the permanent plumbing of a house or apartment, are frequently injured and in many instances their appearance ruined, by the practice of placing dish pans therein during the operation of washing dishes and the like. The rubbing of the dish pan against the enamel scratches the latter, the faucets frequently interfere with the handling of the articles being washed, the enameled surface of the sink is frequently stained by the overflow from the dish pan, and the waste pipe very commonly becomes choked with garbage or other refuse that is suspended in the water of a dishpan when the latter is emptied into the sink at the end of the washing operation. One of the objects of the present invention is to overcome these objections by providing a portable sink that will be extremely simple in construction and in which dishes, fruit, or similar articles may be readily and conveniently washed or cleansed.

A further object is to provide means whereby the water or other fluid contained within the receptacle may drain off when desired.

A further object is to provide means for straining the waste liquid so as to prevent foreign matter from entering the waste pipe of the sink, thereby protecting the waste pipe from clogging.

The invention will be hereinafter fully set forth and particularly pointed out in the claims.

In the accompanying drawing:—Figure 1 is a perspective view illustrating my invention. Fig. 2 is a longitudinal sectional view thereof. Fig. 3 is a transverse sectional view thereof.

Referring to the drawing, 10 designates a receptacle of any suitable or preferred

form. In the construction shown the sides 11 and bottom 12 are formed in one piece, the ends 13 being united to the ends of said sides and bottom by folding over the meeting edges, thereby forming a rectangular receptacle. The upper edges of the receptacle are braced by a rod 14, the edges of the sides and ends being bent over said rod to retain the latter in position. Secured to the bottom of the receptacle, in any suitable manner, are sockets 15 in which are retained rubber pads or feet 16, so as to permit the receptacle to be placed upon any surface or support without scratching. The receptacle is preferably formed of any desired sheet metal, and the bottom 12 is provided with an opening 17 surrounded by an annular depression or shoulder 18. A metallic sleeve 19 extends through the opening 17 and is provided with an annular flange that fits within the depression 18, so that the top face of the flange is flush with the top face of the bottom 12. By this means I form an outlet opening provided with a rigid wall, said opening being closed, when desired, by a stopper 20 provided with a depending ring 21 to which is attached one end of a securing chain 22, the other end of said chain being secured to the under face of the bottom 12 in suitable manner, as indicated at 23. The stopper is somewhat tapering in form so as to permit a portion thereof to project above the bottom of the receptacle, thereby providing sufficient surface to allow the stopper to be readily grasped when it is desired to remove the stopper.

On opposite sides of the opening in the bottom of the receptacle and extending transversely of the latter, are guides 26 constructed to receive flanges 27 secured to the longitudinal edges of a strainer 28, the front end wall of which is made sufficiently high to form an abutment 29 which contacts with the front wall of the receptacle to limit rearward movement of the strainer. The rear end wall of the strainer is reduced in height sufficiently to permit said wall to clear the lower end of the sleeve 19. A handle 30 is provided for the ready manipulation of the strainer, and the receptacle 10 may also be provided with handles 31 for the convenient handling thereof. It will be noted that while the rear end wall of the strainer will

clear the lower end of sleeve 19 it will not clear the ring 21 when the stopper is in position, thereby preventing removal of said strainer without first removing the stopper. 5 In this manner accidental separation of the parts is prevented.

In practice, when it is desired to use my portable sink, the stopper 20 is placed in the outlet and the receptacle is filled to the 10 desired extent with water. The receptacle may then be moved to any desired place. After washing the articles placed therein the receptacle is placed within a kitchen sink, or other suitable place, and upon 15 moving the stopper all liquid within the receptacle will run out and pass into the waste pipe, passing first through the strainer 28. After the receptacle has been emptied the strainer may be removed from its guides and 20 the solids that have been retained thereby may be disposed of in any suitable or desired manner.

Having thus explained the nature of my invention and described an operative manner of constructing and using the same, although without attempting to set forth all of the forms in which it may be made, or all 25 of the forms of its use, what I claim is:—

1. A portable sink of the character described comprising a receptacle having an outlet opening in its bottom, spaced apart guides secured to the underside of said receptacle on opposite sides of said opening, said guides extending to the front wall of 30

said receptacle and a strainer slidably 35 mounted in said guides, the front end of said strainer being higher than the remaining end and sides and forming an abutment co-operating with the front wall of the receptacle to limit rearward movement of the 40 strainer.

2. A portable sink of the character described comprising a receptacle having an outlet opening in its bottom, a stopper for said opening having a ring secured to its 45 underside, a chain connecting said ring to the underside of said receptacle, and a strainer slidably and removably connected to the underside of said receptacle, and the rear wall of said strainer being high enough 50 to contact with said ring when the stopper is in operative position.

3. A portable sink of the character described comprising a receptacle having an outlet opening in its bottom, a strainer slidably 55 engaging said bottom and located beneath said opening, the front end of said strainer being higher than the remaining end and sides to form an abutment co-operating with the front wall of the receptacle 60 to limit rearward movement of the strainer.

In testimony whereof I have hereunto set my hand in presence of two subscribing witnesses.

THOMAS R. PEREGOY.
